CLOSURE

Robert B. Le Roy, Rutherford, N. J., assignor to
Bemis Bro. Bag Company, St. Louis, Mo., a
corporation of Missouri

Application February 26, 1944, Serial No. 524,011

6 Claims. (CL 229—62)

This invention relates to closures, and with regard to certain more specific features, to closures for bag ends and the like.

Among the several objects of the invention may be noted the provision of a bag closure which incorporates an auxiliary trap or guard against movement into the bag of moisture and the like which may have penetrated beyond a cover tape such as in common use; the provision of a closure of the class described which protects the threads of the sewn seam often used for attaching the cover tape, or even when the cover tape is not used; the provision of a seam of the class described which is at tight at its ends as at its mid portions; and the provision of a closure of the class described which may be partially located and attached to a bag at the bag factory and which may finally be conveniently closed by a bag packer after a bag has been filled. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a plan view of a paper blank from which the invention is developed;

Fig. 2 is a perspective view showing an end of said blank with certain preliminary folds therein;

Fig. 3 is a top plan view of the blank of Fig. 2, parts being broken away;

Fig. 4 is a plan view of a completely folded cuff made from the blank and ready for application to a bag end;

Fig. 5 is a side elevation of the cuff of Fig. 4;

Fig. 6 is a vertical section taken on lines 6—6 of Fig. 5, looking upwardly and showing in dotted lines the relative position of the bag to which the cuff is applied;

Fig. 7 is a side elevation of a bag showing at the right, by broken away lines, a partial attachment of the closure, and at the left showing the closure drawn partially open for loading of the bag by the packer; and,

Fig. 8 is a side elevation of a bag showing completion of the closure embodying the invention, including a cover strip as finally sewn in position.

Similar reference characters indicate corre-

sponding parts throughout the several views of the drawing.

Referring now more particularly to Fig. 1, there is shown at numeral 1 an elongate blank 5 having diagonally opposite ends tabs 3 and 5. This blank is preferably composed of craft paper or similar sheet material. It is folded along the parallel lines 7, 9, 11, 13 and 15 to produce, as indicated in Fig. 2, downwardly turned edges or skirts 17 and 19 from the upper edges of lateral panels 21 and 23. Panels 21 and 23 are joined by intermediate panels 25 and 27. The short legs of the sectional W shape are intermediate its lateral longer legs, and the edges 17 and 19 are turned down with respect to the latter. Lines 9 and 13 are coaxial respectively with the inner edges of the tabs 3 and 5. Thus is formed a W-shaped gusset having upper hooking edges.

Each tab 3 and 5 forms an extension after 20 folding as indicated at one end by E in Fig. 2. This is folded on a fold line 31 to enclose the open end of the W-shaped gusset. The extension E is manipulated during folding so as to bring its portion of the depending edge 17 under 25 the depending edge 19 associated with the panel 23. This produces the cuff shown in Figs. 4 and 5, which is in effect a gusset closed in at its ends and provided with an upper marginal skirt. The cuff is then ready for insertion into a bag 30 end with the marginal portions 17, 19 telescoping outside entirely around the bag. In Fig. 6 the solid lines show the cuff of Figs. 4 and 5. The dash lines 29 indicate the locations of bag 35 edges between the continuous skirt 17, 19 and the gusset parts of the cuff which are within the bag mouth.

In Fig. 7 the cuff is shown in final position on the right-hand side of the bag. The bag manufacturer makes a permanent fastening on this 40 side of the bag by applying an adhesive or the like 30 under one or both sides of the skirt 17 or 19. This allows withdrawal of the other end of the cuff from the bag mouth by the bag packer. The bag may then be filled through opening 45 O. The packer then recloses the bag mouth by telescoping the left-hand end of the cuff into position with the skirt portions outside of the bag mouth.

After having thus filled and closed the bag, the 50 packer applies an inverted V-shaped cover strip of the type generally used in the industry and indicated at numeral 33. This cover strip 33 has sides which reach down preferably about flush with the lower edges of the turned-down skirt 17, 19. It is finally sewn into position by means

of the stitching passing through the opposite sides of the cover strip, the skirt 17, 19 and the upper portions of the panels 21 and 23. This sewing does not intersect the shorter intermediate or central panels 25 and 27. These along with the lower portions of the panels 21 and 23 extend down into the bag, thus forming of the gusset an accordion-shaped trap reaching from corner to corner of the bag to prevent any moisture which might pass the seam formed in connection with the cover strip from proceeding further into the bag. It is to be understood that the stitching 35 may be applied without the cover strip or adhesive may be used as a closure without the cover strip. It would be applied between the upper marginal portions of panels 21 and 23. Or, if desired, the cover strip may be attached by adhesive instead of by stitching. In any event it may be desirable to dip the entire seam into wax or other waterproofing compound after the bag has been filled and closed. This provides exterior protection.

Since the W-shape of the gusset 21, 23, 25 and 27 is quite expansive, like a bellows, the trap is effective in any such expanded condition of the sides of the bag as may be caused by its filling. Furthermore, the sealing effect of the bellows extends clear to the end of the bag at its corner where the turned-over extensions 3 provide a complete internal guard throughout the entire periphery of the bag, including points adjacent to its corners.

Another advantage of the invention is that the W-shaped gusset acts as a thread protector for the seam when chemicals are packed which are unfriendly to threads. The gusset holds the contents of the bag away from the threads, particularly if turned over to apply the weight of the contents to the gusset.

It is to be understood that the invention is applicable to the bottom of a bag as well as top, in which case the bag manufacturer completes all operations thereon, since this end of a bag does not require to be left partially open for filling.

It will also be understood that the gusset-forming panels 21, 23, 25 and 27 may have substituted therefor other gusset forming shapes, the primary requisite being that there shall be enough loose accordion-like material between the skirts 17 and 19 to provide for stretching of the closure when the contents of the bag separate its opposite sides.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. A closure for a bag end or the like comprising an expandable gusset strip portion having an expandable portion and marginal portions, said expandable portion being inserted into the bag end to place the marginal portions of the gusset strip inside and adjacent to the marginal portions of the bag, outside skirt portions extending from the marginal portions of the strip and folded to engage the outside marginal portions of the bag, means for fastening the skirts to said marginal portions of the bag, an inverted V-shaped cover strip enclosing said skirts, and stitching passing only through said cover strip,

said skirts and said marginal portions, whereby said expandable portions of the gusset are left free for expansion.

2. A closure for bags and the like comprising an expandable gusset strip located in the end of the bag, said gusset portion comprising relatively wide side panels and relatively narrower connecting panels therebetween, skirt portions extending from the outer edges of said side panels and engaging the outside marginal portions of the bag, and stitching passing through said skirt portions, the upper portions of said relatively wide panels and through the marginal portions of the bag but not through said relatively narrow panels.

3. A closure for bags and the like comprising an expandable gusset strip inserted into the end of the bag, said gusset strip comprising relatively wide side panels and relatively narrow connecting panels therebetween, skirt portions extending from the outer edges of said wide panels and engaging the outside marginal portions of the bag, an inverted V-shaped cover strip covering said skirt portions and enclosing the mouth of the bag and the gusset strip, and stitching passing through the opposite sides of the cover strip, the skirt portions and only the upper portions of the wide panels.

4. A closure for a bag or like tubular article comprising a cuff having a cross section including a gusset-forming part insertable into the mouth of the bag and an outer folded portion located near the edge of said mouth, means extending from said folded edge providing a depending skirt engageable with the outside marginal portions of said bag, and folded ends forming end portions of the cuff to enclose the ends of the gusset, said folded over portions carrying the skirt portions around the corners of the bag mouth, an inverted V-shaped cover strip overlying said skirt portions and stitching passing through said cover strip and underlying parts.

5. A one-piece member for forming a bag closure, comprising a strip, tabs at ends of said strip which tabs are oppositely directed longitudinally of the strip, each tab being narrower than the width of the strip, fold lines including parts traversing said tabs for determining folded skirt portions for outside engagement with the margins of the bag, fold lines in the strip for forming a gusset, each of which lines is coaxial with an edge of a tab whereby adjacently located panels may be folded to form gusset portions and whereby said tabs may be folded around the ends of said gusset portions and against opposite ones of said panels to form a cuff of equal width throughout.

6. A one-piece member for forming a bag closure, comprising a strip, tabs at opposite diagonal corners of said strip which tabs are oppositely directed longitudinally of the strip, each tab being narrower than the width of the strip, fold lines near opposite edges of said strip and respectively traversing said tabs for determining skirt portions to engage the margins of a bag, a fold line along the center of the strip located centrally between said tabs, and fold lines parallel to said central fold line each of which is coaxial with an edge of a tab whereby adjacently located panels may be folded to form a gusset portion, and whereby said tabs after folding down of said skirts may be folded around the ends of said gusset portion and against opposite ones of said panels to form a cuff of equal width throughout.
